UNITED STATES PATENT OFFICE

2,243,291

CONVERSION OF HYDROCARBON OILS

Jean Delattre Seguy, Chicago, Ill., assignor to
 Universal Oil Products Company, Chicago, Ill.,
 a corporation of Delaware

Application August 31, 1939, Serial No. 292,880

3 Claims. (Cl. 196—49)

This invention relates to an improved cracking system involving a combination of interdependent cracking steps, comprising vapor-phase cracking, mixed phase cracking and reforming which cooperate to produce from the charging oil and intermediate liquid conversion products of the process high yields of gasoline or relatively light gasoline fractions of high antiknock value, normally gaseous products containing a high proportion of polymerizable olefins and minor yields of 10 good quality liquid residue.

The vapor-phase cracking step of the system employs as charging stock a reflux condensate, formed by fractionation of the vaporous conversion products of the process, which has an end-boiling point of the order of 600 to 650° F., or thereabouts, and is substantially devoid of free carbon (containing say 0.01% or less as determined by the Conradson method). This material is cracked in essentially vaporous state under 15 conditions regulated to produce only a small amount of decomposition (10% or thereabouts), and the resulting conversion products are commingled with the hydrocarbon oil charging stock for the process and the mixture is separated by fractionation into gases and vapors having an end-boiling point of the order of 600 to 650° F. and higher boiling liquid fractions.

The latter are separately cracked at relatively high superatmospheric pressure under mixed phase conditions (70 to 95% vapor generation at the outlet of the cracking coil) to produce substantial quantities of gasoline and lower and higher boiling fractions. The conversion products of the mixed phase cracking step are separated at substantially reduced pressure relative to that employed in the mixed phase cracking zone into vapors and residual liquid. The residual liquid is recovered as a product of the process and the vapors are supplied to the same separating zone to which the charging stock and the conversion products of the vapor-phase cracking step are supplied, whereby their high-boiling components are included in the cracking stock supplied to the mixed phase cracking step and their lower boiling components of 600 to 650° F., or thereabouts, end-boiling point are commingled in this zone with vaporous components of the charging stock and of the conversion products of the vapor-phase cracking step which have a corresponding end-boiling point.

These commingled vapors are fractionated to condense their relatively heavy components as the aforementioned reflux condensate which is supplied to the vapor-phase cracking step and

to form a lighter condensate consisting essentially of heavy gasoline fractions. This latter condensate is reformed under cracking conditions of elevated temperature and substantial superatmospheric pressure regulated to produce therefrom high yields of gasoline of improved antiknock value. The resulting reformed products are separated into vapors and residual liquid fractions and the latter are supplied to the same vaporizing and separating zone to which the conversion products of the mixed phase cracking step are supplied, while the vapors are supplied to the aforementioned fractionating zone wherein said reflux condensate supplied to the vapor-phase cracking step and said lighter condensate supplied to the reforming step are derived.

The fractionated vapors of the desired end-boiling point are removed as the overhead vaporous stream from this fractionating zone, subjected to condensation and the resulting distillate, which constitutes the high antiknock gasoline product of the process, is separated from the remaining uncondensed gases.

The advantageous and cooperative manner in 25 which the various steps of the process are combined to produce the desired results will be more apparent with reference to the accompanying drawing and the following description thereof. The drawing is diagrammatic and illustrates one 30 specific embodiment of the process flow provided by the invention.

Referring to the drawing, the vapor-phase cracking coil 1, to which is supplied a clean cracking stock of relatively low end-boiling point and 35 of substantially negligible free-carbon content, is disposed in furnace 2 and the oil passing through this coil is substantially completely vaporized and heated to the desired outlet cracking temperature, the conditions of temperature, pressure and conversion time in this zone being correlated to give only a relatively small amount of cracked products (say 10%, or thereabouts) in the heated products discharged therefrom. These 40 products are directed from coil 1 through line 3 and valve 4 to separating and fractionating column 5 and, preferably, are sufficiently cooled to prevent substantial further cracking thereof prior to their introduction into the latter zone. In the case here illustrated, this cooling is accomplished by directly commingling a suitable 45 cooling fluid with conversion products passing through line 3 and may be assisted, when desired, by pressure reduction as the products pass through valve 4 in this line.

50 I may employ a portion or all of the hydro-

carbon oil charging stock for the process as cooling material in line 3 by directing the same from pump 8, to which it is supplied through line 6 and valve 7, through line 9, line 10 and valve 11 into line 3.

Vaporous products from the mixed phase cracking step are also supplied to zone 5 and, when desired, may be cooled, as will be later described, and commingled with the vapor-phase cracked products in line 4 to effect a portion or all of the desired cooling of the latter.

The commingled materials supplied to separating and fractionating column 5 are therein separated into an overhead stream of vapors and gases, which has an end-boiling point of the order of 600 to 650° F., and bottoms which comprise the higher boiling components of the commingled materials and which will vary in composition, depending upon the nature of the charging stock employed, but will have an initial boiling point of the order of 600 to 650° F.

The charging stock may be any desired type of hydrocarbon oil ranging from light distillate to crude petroleum, reduced crude or the like and in addition to the aforementioned provision for commingling charging stock with the conversion products being supplied to zone 5, I provide for introducing regulated quantities of the charging oil, when desired, directly into column 5 at any desired point in this zone for the purpose of assisting cooling and fractionation therein. Line 12 and valve 13, communicating with line 9 and column 5, are provided in the case here illustrated for introducing charging oil directly into the latter zone.

Bottoms from column 5 are directed therefrom through line 14 and valve 15 to pump 16 by means of which they are supplied through line 17 and valve 18 to mixed phase cracking coil 19. This coil is disposed in furnace 20 and the oil passing therethrough is heated to the desired cracking temperature, preferably at substantial superatmospheric pressure, the conditions of temperature, pressure and conversion time in this zone being correlated to produce high yields of gasoline from the oil supplied thereto under mixed phase cracking conditions. Normally, from 70 to 95%, or thereabouts, of the conversion products discharged from coil 19 will be in vaporous state and the total vaporous and liquid conversion products may be directed through line 21, valve 22, line 23 and valve 24 into vaporizing and separating chamber 25 or, when desired, they may first be supplied through line 26 and valve 27 into reaction chamber 28.

When chamber 28 is employed, it is preferably operated at a relatively high superatmospheric pressure which may be substantially the same or somewhat lower than that employed at the outlet of coil 19. The reaction chamber is preferably insulated to conserve heat, although insulation is not indicated in the drawing, so that the products supplied to this zone, and particularly their vaporous components, are subjected to appreciable continued cracking as they pass therethrough. Both vaporous and liquid conversion products are withdrawn in commingled state from the lower portion of chamber 28 and directed through line 29, valve 30, line 23 and valve 24 into vaporizing and separating chamber 25.

Chamber 25 is operated at a substantially reduced pressure relative to that employed at the outlet of coil 19 and also at a substantially lower pressure than that employed in chamber 28, when the latter zone is utilized, whereby the liquid con-

version products supplied to this zone are appreciably further vaporized, leaving a relatively heavy liquid residue which is removed from the lower portion of the chamber through line 31 and valve 32 to cooling and storage, or elsewhere, as desired.

The vapors supplied to and evolved in chamber 25 are separately removed from this zone through line 33 and they may be supplied directly through valve 34 in this line and through line 3 to separating and fractionating column 5 or, when desired, they may first be cooled by passing the same through cooler 35 which communicates with line 33 through lines 36 and 38 controlled by the respective valves 37 and 39.

The relatively clean vapors from the upper portion of column 5 which, as previously mentioned, have an end-boiling point of the order of 600 to 650° F. and which include vaporous and gaseous components of this end-boiling point derived from the total commingled materials supplied to column 5, are directed through line 40 and valve 41 to fractionator 42 wherein they undergo fractionation in commingled state with vaporous products of the reforming step of the process, which latter are supplied to the fractionator, as will be later described. The heavy components of the commingled vapors are condensed in fractionator 42 to form the aforementioned relatively clean cracking stock supplied to coil 2 and, in the preferred embodiment of the invention, this material has an end-boiling point of the order of 600 to 650° F. and contains only a negligible amount of free carbon (for example, 0.01%, or less, as determined by the Conradson test). The vapor-phase cracking stock is directed from fractionator 42 through line 43 and valve 44 to pump 45 which supplies the same through line 46 and valve 47 to cracking coil 1.

Components of the vapors supplied to fractionator 42 of lower boiling characteristics than the materials supplied to coil 1 are further fractionated to form a light overhead vaporous stream consisting essentially of normally gaseous products and light gasoline fractions of high antiknock value (such as, for example, those boiling up to approximately 250 to 350° F., or thereabouts) and form a light condensate which consists essentially of heavier gasoline fractions. This light condensate may have an initial boiling point ranging, for example, from 200 to 300° F., or thereabouts, and an end-boiling point of from 400 to 450° F., or thereabouts, and is directed from the fractionator through line 48 and valve 49 to pump 50 by means of which it is supplied through line 51 and valve 52 to reforming coil 53.

The reforming coil is disposed in furnace 54 and the light condensate passing through this zone is heated under cracking conditions of elevated temperature, substantial superatmospheric pressure and conversion time regulated to produce therefrom high yields of lighter gasoline fractions of materially improved antiknock value. The resulting conversion products are directed from coil 53 through line 54 and valve 55 into separating chamber 56 and preferably cooled in any desired well known manner prior to their introduction into the latter zone sufficiently to prevent their excessive further conversion. As an example of one specific means of accomplishing this, line 57, having valve 58 and communicating with line 54, is provided in the case here illustrated for directly commingling a suitable cooling oil with the

stream of conversion products passing through line 54 and, when desired, cooling may also be assisted by substantially reducing the pressure on the stream of conversion products as they pass through valve 55 in line 54.

The temperature and pressure conditions employed in chamber 56 are regulated to separate the materials supplied thereto into relatively clean vapors which include gases, gasoline fractions and materials boiling up to approximately 600 to 650° F., and leave the higher boiling components of the materials supplied to chamber 56 in liquid state. The relatively clean vapors are directed from chamber 56 through line 57 and valve 58 to fractionator 42 wherein they are subjected to fractionation, as previously described, and the residual liquid is separately removed from chamber 56 and directed therefrom through line 59 and valve 60 to pump 61 and thence through line 62 and valve 63 into separating chamber 25 wherein their heavy components commingle with the residual liquid fractions removed from this zone through line 31 and valve 32, while their lower boiling components are vaporized and supplied with the other vaporous fractions from this zone to column 5. Pump 61 may be omitted when chamber 56 is operated at higher pressure than that employed in chamber 25.

The overhead vaporous stream resulting from fractionation in fractionator 42 is directed therefrom through line 64 and valve 65 to condensation and cooling in condenser 66 wherefrom the resulting distillate and uncondensed gases are directed through line 67 and valve 68 to collection and separation in receiver 69. The uncondensed gases are removed from the receiver through line 70 and valve 71 and directed to storage or elsewhere, as desired. Distillate collected in receiver 69, which comprises the final motor fuel product of the process and consists of gasoline fractions of high antiknock value having an end-boiling point of the order of 250 to 350° F., or thereabouts, is supplied from receiver 61 through line 72 and valve 13 to storage or to any further desired treatment.

When desired, regulated quantities of the distillate collected in receiver 69 may be returned by well known means, not illustrated in the drawing, to the upper portion of fractionator 42 to serve as a cooling and refluxing medium in this zone and it is also within the scope of the invention, when desired, to utilize this material for cooling the conversion products of the reforming operation in line 54 by supplying the same thereto through line 57 and valve 58.

It will, of course, be understood that any well known expedients for regulating temperatures at various points in the system and for controlling the boiling range characteristics of the intermediate liquid products, such as, for example, the vapors removed from chamber 5 and from chamber 56, may be employed in conjunction with the means illustrated. For example, suitable fractionating means such as bubble trays, perforated pans or the like may be provided in the upper portion of chamber 56 and a suitable cooling and refluxing medium such as, for example, a portion of the light condensate from fractionator 42 may be supplied at the desired temperature to the upper portion of this zone as a cooling and refluxing medium. Likewise, light or heavy condensate from fractionator 42 may be supplied at the desired temperature to the upper portion of column 5 as a cooling and re-

fluxing medium. Similar cooling means may also be employed in chamber 25 to control the characteristics of the vapors and the residual liquid products separated in this zone and cooling may be employed, when desired, in line 23 in any well known manner, not illustrated.

As an example of one specific operation of the process herein provided, employing as charging oil a Muskegon topped crude, the condensate supplied to the vapor phase cracking coil has an end-boiling point of approximately 650° F. and is heated therein to an outlet temperature of approximately 1000° F. with a superatmospheric pressure at this point in the system of approximately 150 pounds per square inch. Substantially the same pressure is employed in the succeeding separating and fractionating column and the top temperature of the latter zone is maintained at approximately 700° F., a portion of the charging oil being supplied to the fractionating section of this zone and another portion thereof being commingled with the stream of conversion products passing to the separating section of this zone from the vapor-phase cracking coil.

The mixed phase cracking coil, to which bottoms from the aforementioned separating and fractionating column are supplied, is operated with an outlet temperature of approximately 935° F. and an outlet pressure of approximately 200 pounds per square inch. The succeeding reaction chamber is operated at substantially the same pressure and both vaporous and liquid conversion products from this zone are supplied to the reduced pressure vaporizing and separating chamber which is operated at a superatmospheric pressure of approximately 75 pounds per square inch, the conversion products being cooled to a temperature of approximately 850° F. prior to their introduction into this zone, while the temperature of the vaporous stream leaving this zone is maintained at approximately 780° F. and further cooled prior to its introduction into the separating and fractionating column to which the charging stock and products of the vapor-phase cracking operation are supplied.

The fractionator from which the condensate supplied to the vapor-phase cracking operation and the lighter condensate supplied to the reforming operation are derived, is operated at a superatmospheric pressure of approximately 100 pounds per square inch and said light condensate supplied to the reforming operation has a boiling range of approximately 220 to 450° F. This material is heated in the reforming coil to an outlet temperature of approximately 1025° F. at a superatmospheric pressure, measured at the outlet of the coil, of approximately 750 pounds per square inch and the resulting heated products are cooled prior to their introduction into the succeeding separating chamber to a temperature of approximately 760° F., this separating chamber being operated at a superatmospheric pressure of about 100 pounds per square inch and the temperature of the vaporous stream removed therefrom and supplied to the fractionator being maintained at approximately 685° F., the liquid products from this zone being supplied to the aforementioned reduced pressure vaporizing and separating chamber.

The end-boiling point of the gasoline recovered from the fractionated vapors is approximately 300° F., amounts to approximately 48% of the charging oil and has an octane number of approximately 72. The other products of the

process comprise about 32%, based on the charging oil, of residual liquid of good fuel oil characteristics and uncondensed gases which contain a high proportion of polymerizable olefins.

It will be understood, of course, that the temperature and pressure conditions given in the foregoing example may be varied considerably, depending upon the type of charging stock undergoing treatment and the desired quality of the final residual liquid and gasoline products, and it is within the skill of one familiar with the cracking art to vary the operating conditions to suit requirements. Such changes do not constitute a departure from the invention so long as its teachings with respect to the characteristics of the cracking stocks supplied to the vapor phase cracking step are observed while maintaining mild vapor-phase cracking conditions in this zone, mixed phase cracking conditions in the heavy oil cracking step of the system and reforming conditions in the cracking step to which the lighter condensate is supplied.

I claim as my invention:

1. A hydrocarbon oil conversion process which comprises introducing cracked vapors and charging oil for the process to a separating and fractionating zone, therein separating a vaporous product having an end-boiling point of from about 600 to 650° F. and a heavier liquid product, further fractionating said vaporous product in a second fractionating zone to form a light gasoline fraction of high anti-knock value, a heavy gasoline fraction of relatively low anti-knock value, and a reflux condensate heavier than gasoline having an end-boiling point of from about 600 to 650° F., subjecting said reflux condensate to relatively mild vapor phase cracking such as to effect not substantially in excess of 10% decomposition thereof per pass through the cracking zone, introducing the resultant products to said separating and fractionating zone, subjecting said heavier liquid product to mixed phase cracking under conditions adequate to produce therefrom a greater quantity of gasoline than

is formed by said vapor phase cracking, introducing vaporous products of the mixed phase cracking step to said separating and fractionating zone, independently subjecting said heavy gasoline fraction to cracking conditions adequate to enhance the anti-knock value thereof, and supplying resultant vaporous products to said second fractionating zone.

2. A hydrocarbon oil conversion process which comprises introducing cracked vapors and charging oil for the process to a separating and fractionating zone, therein separating a vaporous product having an end-boiling point of from about 600 to 650° F. and a heavier liquid product, further fractionating said vaporous product in a second fractionating zone to form a light gasoline fraction of high anti-knock value, a heavy gasoline fraction of relatively low anti-knock value, and a reflux condensate heavier than gasoline having an end-boiling point of from about 600 to 650° F., subjecting said reflux condensate to relatively mild vapor phase cracking such as to effect not substantially in excess of 10% decomposition thereof per pass through the cracking zone, introducing the resultant products to said separating and fractionating zone, subjecting said heavier liquid product to mixed phase cracking under conditions adequate to produce therefrom a greater quantity of gasoline than is formed by said vapor phase cracking, separating the mixed phase conversion products into vapors and residue in a reduced pressure vaporizing zone, introducing the vapors to said separating and fractionating zone, independently subjecting said heavy gasoline fraction to cracking conditions adequate to enhance the anti-knock value thereof, and supplying resultant vaporous products to said second fractionating zone.

3. The process as defined in claim 2 further characterized in that liquid products of the heavy gasoline reforming step are introduced to said reduced pressure vaporizing zone to commingle with the residue separated therein.

JEAN DELATTRE SEGUY.
